UNITED STATES PATENT OFFICE.

REGINA L. PARENT, OF MINNEAPOLIS, MINNESOTA.

CHILD'S GARMENT.

1,317,214.

Specification of Letters Patent. Patented Sept. 30, 1919.

Application filed September 30, 1918. Serial No. 256,203.

To all whom it may concern:

Be it known that I, REGINA L. PARENT, a citizen of the United States, residing at Minneapolis, in the county of Hennepin and 5 State of Minnesota, have invented certain new and useful Improvements in Children's Garments; and I do hereby declare the following to be a full, clear, and exact description of the invention, such as will enable 10 others skilled in the art to which it appertains to make and use the same.

My present invention, particularly, relates to garments for infants and children, such, for instance, as are especially adapted to be 15 worn out of doors in cold weather. The invention is directed particularly to an improved shoulder and sleeve structure and provides a garment of the character indicated, which may be cheaply constructed, 20 which will have a neat appearance, and which will be highly efficient for the purposes had in view.

The invention is illustrated in the accompanying drawings, wherein like characters 25 indicate like parts throughout the several views. Referring to the drawings;

Figure 1 is a plan view showing the sheet or blank from which the body of the garment is formed;

30 Fig. 1^a is a plan view of a supplemental shoulder strip, two of which are employed in the completed garment;

Fig. 2 is a front elevation showing the completed garment with one sleeve turned 35 out and the other turned inside of the garment; and Fig. 3 is a view corresponding to Fig. 2, but with some parts sectioned and the garment partly opened up.

This improved garment is adapted to be 40 made from a single piece of cloth or from a single sheet made up of several sections. When the cloth is of the proper width, the body of the garment will preferably be made of a single piece, but when the cloth is too 45 narrow for that result, then the single body forming sheet may be made up, for instance, of a back forming portion 5^a, and front portions or flaps 5^b which may be stitched together on the dotted lines 5^c.

50 The sleeves are preferably made with closed ends so that when turned into the garment, they will afford pockets. The under side portions of such sleeves are formed by sleeve strips 6 that are primarily attached 55 to the body sheet 5 at their lower ends. The

back forming portion 5^a is provided with curved edges 7 and sleeve strips 6 that are primarily attached to the body sheet 5 at their lower ends. The back forming portion 5^a is provided with curved edges 7 and with 60 neck forming notches 8, while the front forming portions 5^b are formed with curved edges 9 and with neck forming notches 10. The curved edges 7 and 9 are formed by cutting darts out from between the sleeve forming flaps 6 and back forming portions 5^a and front forming portions 5^b, respectively. 65

The tops of the sleeves and the tops of the shoulders of the garment are formed by 70 shoulder forming strips 11 shown in detail in Fig. 1^a. In forming the body of the garment, the edges of the shoulder and sleeve forming strips 11 are stitched to the curved edges 7 and 9 and to the edges of the under 75 sleeve forming strips 6, as shown in Figs. 3 and 4, on lines marked 12 on Figs. 3 and 4. In this way, the shoulder of the garment is completed and short sleeves with closed 80 outer ends are also completed.

The seams 12 are preferably of the French seam type. The edges of the front forming flap or portions 6^b are arranged to be overlapped and connected by suitable buttons and buttonholes 13. The garment will preferably be provided with an attached hood. This hood, indicated as an entirety by the numeral 14, may be of any suitable construction, so far as the present invention is concerned, and as shown, is directly stitched to 85 the upper edges of the back and front forming portions 6^a and 6^b of the garment body, and to the upper ends of the combined shoulder and sleeve forming strips 11. 90

What I claim is:

1. A child's garment comprising back and front forming portions with attached undersleeve forming strips, and combined shoulder and sleeve forming strips stitched to the upper edges of said back and front forming portions and stitched also to the edges of said undersleeve strips. 95 100

2. A child's garment comprising back and front forming portions with attached undersleeve forming strips, and combined shoulder and sleeve forming strips stitched to the upper edges of said back and front forming portions and stitched also to the edges of said undersleeve strips, and a hood attached 105 to the upper edges of said back and front 110

forming portions and to the upper ends of said combined shoulder and sleeve forming strips.

3. A child's garment, the body of which is made from a single sheet and two combined shoulder and sleeve forming strips, said sheet having back and front forming portions and attached undersleeve forming strips, the edges of said combined shoulder and sleeve forming strips being stitched to the upper edges of said back and front forming portions, and also being stitched to the edges of said undersleeve strips.

4. A child's garment, the body of which is made from a single sheet and two combined shoulder and sleeve forming strips, said

sheet having back and front forming portions and attached undersleeve forming strips, the edges of said combined shoulder and sleeve forming strips being stitched to the upper edges of said back and front forming portions, and also being stitched to the edges of said undersleeve strips, the sleeves thus formed being closed at their ends and being reversible to afford pockets when turned into the garment.

In testimony whereof I affix my signature in presence of two witnesses.

REGINA L. PARENT.
